BOOKKEEPING MACHINE

William I. Nicholson, Jr., Tulsa, Okla.

Application January 29, 1927, Serial No. 164,594
Renewed November 25, 1932

24 Claims. (Cl. 197—5)

This invention relates to bookkeeping machines.

An important object of the invention resides in the provision of a device in which any chosen record can be selected from a group of records, and positioned with respect to a recording mechanism whereby one or more duplicates of an entry can be mechanically recorded on one or more records simultaneously with the original entry on an entirely different record.

10 Another important object of the invention resides in the provision of a device of the foregoing character in which an original entry either alone or simultaneously with a duplicate entry can be recorded on any selected record to the exclusion of duplicates on separate records.

15 A further object is to provide a group of record holders suitably indexed for selective use as platens for a recording mechanism.

Another object is to provide a novel selector 20 mechanism for selecting any desired object from a group for use either alone or in conjunction with any kind of machine to act upon said object.

Other objects of the invention will become apparent during the course of the following description.

25 In the drawings forming a part of this application, and wherein like numerals are employed to designate like parts throughout the several views:

30 Figure 1 is a plan view of the machine.

Figure 2 is a longitudinal vertical section through the same.

Figure 3 is an enlarged perspective view of the selector mechanism.

35 Figure 4 is a scattered view of part of the selector mechanism.

Figure 5 is an enlarged fragmentary perspective view illustrating the manner of locking an account holder to a typewriter carriage.

40 Figure 6 is a vertical section of the same taken on the line 6—6 of Figure 5.

Figure 7 is a fragmentary section of an account holder.

Figure 8 is a front plan of an auxiliary typewriter carriage.

45 Figure 9 is an enlarged perspective view of the type lever actuating mechanism.

Figure 10 is a side elevation of the same, and

50 Figure 11 is an enlarged detail section of one of the index buttons forming a part of the selector mechanism.

In order that the invention may be more readily understood, I will preface the detail description with a general description of the machine and the functions it is adapted to accomplish.

Referring to Figure 1, a typewriter A of the usual construction is mounted on a suitable support or desk top and has its type lever actuating mechanism connected to the type lever actuating mechanisms of a pair of auxiliary typewriters B and C, located at either side of the central or master typewriter A to the rear thereof, and at the forward end of ways D and E, whereby actuation of the master typewriter will simultaneously actuate corresponding type levers of the auxiliary typewriters B and C.

To the rear of the master typewriter, a group F of records or individual ledger accounts are positioned to be arranged between the two ways D and E so that the account selected for entries may be transferred into the ways for movement into the cooperative relation with the auxiliary typewriters to receive entries therefrom. Each record or account consists of the usual ledger sheet, movable into cooperative relation with the auxiliary typewriter B for the debit entries, and into a similar relation to the auxiliary typewriter C for the credit entries simultaneously with the entry made by the master typewriter A on the journal.

A selector mechanism is provided for each auxiliary typewriter for positioning the record in cooperative relation with either of the auxiliary typewriters to receive impressions therefrom, and includes a selective index G for the auxiliary typewriter B located to the left of the master typewriter, and a selective index H for the auxiliary typewriter C located to the right of the master typewriter, which are employed to set the machine for the selection of the account upon which it is desired to make entries. In this particular illustration of the invention, the auxiliary typewriter B is employed for recording "accounts receivable" and the auxiliary typewriter C is employed for recording "sales", while, of course, the master typewriter is employed for posting both items as well as remarks upon a loose leaf of a journal.

After an account in the group F has been selected by either of the indexes G and H and moved up into cooperative relation with either auxiliary typewriters B or C by other mechanism which will be described hereinafter, and a loose leaf of the journal has been inserted in the master typewriter A, it will be seen that simultaneous posting in the journal and on the ledger sheet may be accomplished by actuation of the master typewriter. In other words, both debit and credit entries may be posted at the same time on dif-

ferent records as for instance, it may be desired to post the following entry:

Debit—Donations..... \$100.00
5 Credit—Vouchers payable..... \$100.00

After these accounts have been selected by indexes G and H, and moved up into cooperative relation with auxiliary typewriters B and C, respectively (loose leaf of journal being in the master typewriter A), the entry will be recorded as follows:

Dec. 30, 1926—Voucher F 65..... \$100.00

The above written on the master typewriter 15 will have recorded through the medium of the auxiliary typewriter on the left a debit of \$100.00 to donations account, and through the medium of the auxiliary typewriter H, a credit of \$100.00 to vouchers payable account, together with the 20 date and voucher number on each account, which is all the information necessary to be posted to the ledger account. The account holders will then be returned to their proper places in the group F. Additional details will be required on 25 the journal sheet, and this is then posted thereon, the keys of the auxiliary typewriters striking against the bare platen. Such additional details will be filled in by writing in the space provided for account names on the journals and 30 offsetting the figures \$100.00 written in as outlined above, the account name "Donations" and, after spacing, the account name "Vouchers payable" and the figures \$100.00 in the credit column on the journal sheet, and in the explanation 35 column will be written "Donations to Red Cross."

The accounts F are all arranged in vertical positions, one behind the other in a suitable partitioned or grooved rack 15 arranged on a support or desk top behind the master typewriter A. In 40 order to select any desired account for positioning parts of the same in cooperative relation to the auxiliary typewriters, the selective indexes G and H are provided, each including as many indexed abutment keys or buttons 16 as there are 45 individual accounts in the group F. I have illustrated sixty (60) keys for each selective index in the present modification, and it will be noted that these keys are arranged in twelve rows of five, extending longitudinally of the machine, and 50 that the buttons of adjacent rows are arranged in staggered relationship, so that abutments for the selector mechanism may be disposed at different distances from the group of records F. The arrangement of the abutments 16 of the selective index G are arranged and numbered thus; whereby the rows transversely of the keyboard will individually contain all numerals ending with the same figure:

60	60	50	39	40	29	30	19	20	9	10
59	49	48	38	38	28	28	18	18	8	8
57	47	46	37	36	27	17	17	7	6	6
55	45	45	35	35	25	26	15	16	5	6
53	43	44	33	34	23	24	13	14	3	4
65	52	42	31	32	21	22	11	12	1	2
51	41									

The arrangement and numbering of the index buttons for the selective index H is just the reverse of the above with the numbering beginning at the left of the index H. The keys or buttons 70 16 of each row transversely of the keyboard are arranged in stepped or banked relation as shown 75 best in Figure 2, in the same manner that the

keys of a typewriter are arranged. One of these buttons 16 is shown clearly in Figure 11, and as all of them are of like construction, a description of one will suffice.

The stem 17 of each button is slidably mounted 80 in a vertical socket 18 in the frame of the machine, and is provided with a yielding detent 19 for cooperation with a pair of recesses 20 in the wall of the socket 18 for retaining the button in a raised position, as shown in full lines in Figure 11, or a depressed position as shown in dotted lines, so that its lower end 21 forms an abutment for another part of the selector mechanism, to be hereinafter described.

In order to raise the depressed buttons 16 90 from their lowered positions, a button elevating mechanism 22 is provided for each selective index G and H, and consists of a vertically movable guided plate 23 positioned beneath each selective index and provided with a plurality of upstanding pins 24 arranged in the same manner as the stems 17 of the buttons thereabove, and in alignment therewith, so that upon elevation of the plate 23, any buttons 16 which are depressed will be raised to the position shown in full lines in 100 Figure 11. Thus, the buttons 16 may be returned to their normal positions. The plate or head 23 is provided with a pin and slot connection with a lever 25 fulcrumed on the frame and equipped with an upstanding handle portion 26. Upon 105 depression of the handle portion 26, the lever 25 will move the plate 23 vertically upon suitable guides 7 provided in a recessed portion 28 of the frame.

It will be understood that the selective index 110 buttons 16 are provided to limit the movement of selector mechanisms movable longitudinally in each of the ways D and E, this selector mechanism comprising in part a finder plate 29, as best seen in Figures 3 and 4. This finder plate 29 is 115 arranged vertically for sliding movement in its guideway and is provided with an elongated horizontally disposed slot 30 extending substantially the entire length of the plate for a purpose which will be presently described.

Extending forwardly from the finder plate 29 is a U-shaped frame 31, the free ends of the frame being secured to the finder plate while the bridge portion is disposed a substantial distance forwardly thereof, as clearly shown in Figures 1 and 125 3, and is provided with a plurality of forwardly extending pins or rods 32 which are arranged in groups of two, the pins of a group being of the same length, and each pair being a little longer than the adjacent pair; the shortest of these 130 pins being arranged at the right side of the U-shaped frame 31. The distance between each pin 32 is the same as the distance between the rows of buttons 16 for cooperation therewith in limiting the movement of the finder plate 29 along 135 its way D or E to arrive substantially opposite the selected account or record in the group F. Thus, if one of the buttons 16 of the selective index G in the first row to the right of the index is depressed, it will be disposed in the path of the 140 movement of the first pin 32 to the right of the frame 31, so that when this frame is moved forwardly, the pin 32 will abut the depressed button 16 and bring the finder plate 29 substantially opposite the chosen account in the group F. Ex- 145 tending forwardly from the frame and parallel to the pins 32 is an elongated actuator rod 33 terminating in a handle 1 forwardly of the selective index, as shown best in Figure 1, to be readily accessible to the operator.

Moved forwardly with the finder plate 29 is an account advancer 34 which is adapted to move the selected account up the auxiliary typewriter. This advancer 34 consists of a pair of relatively movable sections 35 and 36, the upper section 36 of which slides transversely of the machine in the grooved upper edge of the lower section 35, and is provided with a laterally extending hook 37 which is adapted to cooperate with the carriage 10 of the auxiliary typewriter, as will be more fully explained hereinafter. Any suitable anti-friction means may be provided for facilitating the movement of the upper section 36.

This upper section 36 is made to move relative 15 to the lower section 35 so that the upper section can move with the typewriter carriage when moved up into cooperative relation therewith, while the lower part 35 remains stationary because it is prevented from partaking of corresponding movement by its operating means for bringing the advancer forward.

The lower section 35 of the advancer is provided at its lower edge with a forwardly extending flange 38 or trough which is arranged in a plane 25 just slightly lower than the lower edges of the account holders constituting the group F, so that these holders may be slid into the trough 38 of the advancer, suitable anti-friction means being provided if found desirable. This lower section 30 35 is also provided with a horizontal elongated slot 39 extending lengthwise thereof and opening out into the outer edge of the lower section, as best seen in Figures 3 and 4. This slot 39 is in alignment with the slot 30 of the finder plate 29 35 for the passage of a horizontally extending portion 40 of a transfer pin 41; this horizontal portion of the pin extending through the slots 30 and 39, and terminating in a head behind the finder plate, so as to be permanently associated there- 40 with, and yet may move out of the slot 39 and clear an offset portion 42 of an actuating rod 43 of the advancer 34 to permit the advancer to be moved with the selected account up to the auxiliary typewriter without moving the finder plate 45 longitudinally, but permitting the finder to remain in a position to cooperate in returning the account to the group F after the desired entries have been made. This actuator rod 43 extends forwardly of the machine to terminate in a handle 50 3 forwardly of the selective index in an accessible position to the operator of the master typewriter. It is to be noted that the rod 43 is connected to the side of the lower section of the advancer 34 and is offset as at 42 to permit transverse move- 55 ment of the upper section of an account holder, as will be more fully explained hereinafter.

The group F of records comprises a plurality of account or ledger sheet holders 44, each of which consists of relatively movable sections 45 and 46, 60 the upper section 45 being telescoped over the lower section 46 and being movable vertically thereof by a line spacing lever 47 on an auxiliary typewriter carriage 64 cooperating with ratchet teeth 49 formed on the marginal edge of the upper section 45, as clearly shown in Figure 7; the line spacing of the upper section being maintained by its inner corrugated surface 50 cooperating with bowed springs 51 secured to the edge of the lower section 46. This upper section of 65 the ledger sheet holder is provided with suitable clips 46' for securing a larger sheet to the forward face thereof. As will be evident from Figures 5 and 7, the telescoping of the upper section 45 over the lower section 46, provides the upper section 45 with end walls which prevent relative

horizontal movement between the sections 45 and 46.

The lower section of each ledger sheet holder is provided with a laterally extending hook 52 which projects through a slot in the end of the upper section 45 to cooperate with the hook 37 of the advancer 34 in becoming automatically locked in engagement with the auxiliary typewriter carriage to partake of movement corresponding to the carriage as will be more fully explained. The hooks 52 on both the debit and credit record holders extend in the same direction and from the same ends of these holders so that either the debit or credit record holders can be coupled to the carriages of either auxiliary typewriters B or C. The lower edge of the lower section of each account holder is provided with a pair of vertical notches 53 located adjacent the sides thereof, one notch being employed for the debit side of the machine, and the other for the selector mechanism of the credit side. The notches 53 of all of the account holders 44 are arranged in alignment longitudinally of the machine for the passage of an offset portion 54 of an arm 55 secured to the transfer pin 41 of each transfer mechanism. The offset 54 is sufficient to make the arm 55 and transfer pin clear the flange or trough 38 of the advancer plate when the transfer mechanism is actuated to transfer the account holder into the trough 38 of the advancer 34. 105

It will be understood that a transfer pin 41 is provided for each side of the machine, and since the transfer mechanism for the debit side is the same as that of the credit side, a description of one will suffice for both. Each transfer pin 41 110 is adapted to extend through an elongated slot 56 provided along one margin of transfer plate 57, which is movable from under the group F of account holders transversely of the machine and under the finder and advancer plates 29 and 34 115 respectively. The actuating mechanism for each transfer plate 57 consists of a bell crank lever 58 fulcrumed upon the supporting structure, as at 59, and has an elongated arm terminating in an upstanding pin 60 operating in an elongated slot 120 61 of the transfer plate to move the same transversely of the machine. The other arm 62 of the bell crank is pivotally connected to a rod 63 extending forwardly of the machine and terminating in a handle 2 in front of the selective 125 index mechanism within convenient reach of the operator. It will thus be seen that forward movement of the rod 63 at the left of the machine on the debit side will move the transfer plate 57 to the left of Figure 3 beneath the finder and advancer plates forming part of the selector mechanism. 130

The operation of the machine thus far described is as follows:

A button 16 of the selective index G corresponding to the chosen ledger sheet holder of the group F is depressed so as to dispose the lower portion of this button in the path of movement of the proper rod 32 so that when the handle 1 of the finder plate is moved forwardly, the finder plate 140 29 will stop substantially opposite the chosen debit account holder 44. This movement of the finder plate will likewise move the advancer mechanism 34 to a position directly opposite the selected account holder 44 so that the trough or flange 38 145 is in a position to receive the account holder. The forward movement of the finder plate 29 and the advancer 34 will move the offset portion 54 of the pin 41 through the notches in the grouped account holders 44, so that it will stop with this 150

offset portion engaged with the selected account holder 44, and out of contact with the adjacent account holders. Then, by pulling the handle 2 of the transfer mechanism, the bell crank 58 will be swung on its pivot to move the transfer plate 57 to the left of Figure 3, carrying with it the transfer pin 41, which in turn will drag the selected account holder 44 into the trough 38 as the offset portion 40 of the transfer pin moves 5 through the slots 30 and 39 of the finder and 10 advancer to such an extent that the offset portion 40 of the transfer pin will become disengaged from the advancer 34, and permit the advancer being moved forward with the selected account to 15 position the latter in cooperative relation to the auxiliary typewriter to receive impressions therefrom upon actuation of the master typewriter A. The credit side of the machine is operated in exactly the same manner to bring the account 20 holder with the proper ledger sheet into cooperative relation with the auxiliary typewriter C.

When the account holders are moved into the troughs 38 of the advancer 34, the hook 52 of the 25 account holders will be brought into alignment with the hooks 37 of the advancer for cooperative relation with a latch mechanism carried by the auxiliary typewriter carriages, which will now be discussed.

30 The carriage mechanism on the master typewriter A is of the well known usual construction, and has suitable connections with the carriages 64 of the two auxiliary type mechanisms B and C so that actuation of the carriage of the 35 master typewriter will simultaneously operate the carriages of the auxiliary mechanisms in like manner. Each of the auxiliary typewriter carriages is provided with rack bar 65 to cooperate with an escapement on each auxiliary typewriter, 40 which is actuated by the escapement of the master typewriter to feed the carriages transversely of the type levers in step by step fashion. It will be noted that the two auxiliary type mechanisms B and C are located at the forward ends of the 45 ways D and E adjacent the left hand side thereof so that the account holders will present the ledger sheets to these type mechanisms, with their proper columns in correct position to receive impressions from the auxiliary type mechanisms. 50 Each auxiliary typewriter has a carriage 64 which is mounted upon rollers 66 to travel on a suitable track 67 extending transversely of the machine. Each of the auxiliary typewriter carriages is also provided with a roller spring 68 for moving the same to the left upon operation of the 55 escapement.

As shown best in Figure 5, each auxiliary typewriter carriage 64 is provided at its left side with means for locking both the advancer 34 and account holder 44 to the carriage to partake of the 60 same movement thereof, this means consisting of a spring-urged latch 69 fulcrumed at 70 to the carriage, and having a rearwardly projecting arm 71 adapted to hook over hooks 37 and 52 of the advancer and account holders respectively. The other end of the latch 69 is provided with a handle portion 72, by which the latch may be 65 disengaged from the hooks 37 and 52 to release the advancer and account holder after the 70 proper entries have been made, and the account holder is to be restored to its original location in the group F. A spring 73 abuts the latch 69 and a projection 74 of the bracket carried by the carriage for normally retaining the hook 71 of the 75 latch in engagement with the hooks 37 and 52,

and to normally maintain the cam end of the latch in the path of movement of the two hooks whereby they will automatically cause the latch to engage the same when the account holder is moved to typing position with respect to the auxiliary typewriter.

As the advancer mechanism, together with the selected account holder 44, is moved forwardly up to the auxiliary typewriter carriage 64 by means of moving the rod 43 and handle 3 forwardly, the hooks 37 and 52 will cause the latch 69 to become automatically locked therewith, so as to lock the upper section 36 of the advancer, and the account holder 44 to the carriage to partake of the same movements thereof in making entries upon the ledger sheet. With the parts in this position, it will be seen that the line spacing lever 47 may be operated to cooperate with the ratchet teeth 49 of the upper section 45 of the account holder to move the ledger sheet attached thereto vertically for line spacing, as the entries are made. The springs 51 of the lower section of the account holder will maintain the newly adjusted relationship between the two sections 45 and 46 so that the account holder may 100 be returned to the group F with the upper section adjusted so that when it is again moved up to the type mechanism, it will be in proper position to immediately continue entries on the next succeeding line of the ledger sheet. After 105 the entries have been completed, the rod 43 of the advancer is pushed rearwardly. At the same time, the latch 69 is disengaged from the hooks 37 and 52, thereby releasing the account holder and advancer from the carriage and permitting 110 these two elements to be moved rearwardly until they abut the finder plate 29 which has been left in a position opposite the proper location for the account holder in the group. It will be remembered that the transfer pin with its offset arm 54 was left in its position of release from the account 115 holder, so that upon return of the account holder 44 to the finder plate 29, the notch 53 in the account holder will move over the offset portion 54 of the transfer pin so that upon inward movement of the rod 63, the transfer plate 57 will be moved to the right causing the offset portion 40 of the transfer pin to ride in the slot 39 of the advancer and slide the account holder back into its original location among the group of 120 account holders F, with the offset portion 54 of the transfer pin still in line with the aligned notches 53 of the various account holders, so that upon subsequent selection of a chosen account holder, the offset portion 54 of the transfer pin will move 125 longitudinally through the group of account holders, and stop in engagement with the one selected by the selective indexes G or H. The operation of the selector mechanism for the credit and debit sides of the machine is exactly the same, and consequently, from a description of one, the construction and operation of the other will be obvious.

The master typewriter A employed in conjunction with this invention employs 40 keys, using 140 only capital letters of the alphabet, nine (9) ordinals from 2 to 9 and 0 with a dash key at the end of the ordinal row, a number symbol at the end of the first row of letters, a dollar mark at the end of the second row of letters, and a 145 period and a fraction line at the end of the third row of letters. The key levers and type of the auxiliary type mechanisms B and C correspond to those of the master typewriter and are interconnected, as shown in Figures 9 and 10. 150

- The invention contemplates the provision of a number of oscillatory rods or shafts 74 mounted to the rear of the master typewriter and extended beneath the two auxiliary typewriters. Each of these rods 74 is provided with a forwardly extending arm 75 which has a pin and slot connection with an intermediate member 76 fulcrumed at 77 in the master typewriter, and the opposite end of this intermediate lever has a pin and slot connection with a key lever 78 of the master typewriter, which is fulcrumed thereon at 79. Depression of any of the keys of the master typewriter turns the rods or shafts 74 to which the keys are connected through the system of levers just described. 80
- Each of these oscillatory rods 74 is also provided beneath each auxiliary typewriter with an arm 80 extending in the same direction as the arm 75. To the free end of each of the arms 80 is pivotally connected a link 81, the other end of which has a pin connection with an arcuate slot in an auxiliary key lever 82 fulcrumed at 83, and provided with an escapement operating extension 84 in the usual manner, so that an outward and downward movement of the link 81 will swing the type lever 82 on its fulcrum to make an impact against the platen formed by the account holder. Each of the auxiliary typewriter keys 82 is provided with a loop 85 to which key fasteners, not shown, may be shifted, thus eliminating contact which forces type keys up and forward when the master typewriter A is operated. This will permit of writing an explanation on the journal and only on one or either of the accounts on the right or left. This obviously provides for rendering either or both of the auxiliary typewriters B and C inoperative so that individual remarks may be posted upon either ledger sheet simultaneously with the posting on the journal sheet, or both auxiliary typewriter key levers may be prevented from movement to permit individual remarks to be posted on the journal sheet to the exclusion of the ledger sheets associated with the auxiliary typewriters. 90
- Although I have referred to the various type mechanisms as typewriters, it is to be understood that it is within the scope of my invention to employ the invention in conjunction with any kind of recording mechanism, and furthermore, that the invention may be employed to advantage when used in conjunction with one recording mechanism. It is also to be understood that various changes in the construction and arrangement of parts may be resorted to without departing from the spirit of the invention or the scope of the appended claims. 100
- I claim:
1. The combination with a recording mechanism, a group of record holders, each record holder comprising upper and lower relatively movable parts, said upper part having means for attaching a record sheet thereto, ratchet teeth carried by said upper part, means for selecting any one of said record holders and positioning the same in cooperative relation to said recording mechanism, said recording mechanism including a carriage, means on said carriage for engagement with the lower part of the selected record holder, and a line spacing lever carried by said carriage for cooperation with the ratchet teeth of said record holder. 110
  2. In a device of the class described, the combination with a master recording mechanism and auxiliary recording mechanisms on each side operatively connected for simultaneous operation therewith, ways extending to said auxiliary mechanisms, a group of record holders arranged between said ways, and an indexed selector mechanism for each auxiliary recording mechanism for selecting certain of said holders, and means for positioning a selected holder to receive impressions from its respective recording mechanism upon actuation of said master recording mechanism. 120
  3. In a device of the class described, the combination with a recording mechanism, a group of record holders, holder selector means including stepped abutments, selective index means including abutments arranged for movement into the path of the stepped abutments to position the selector means to receive a desired record holder, transfer means for moving a selected record holder from said group to said selector means and for restoring the same to said group, said selector means having means to position the selected record holder in cooperative relation to said recording mechanism, and means for removing said index abutments from the path of said stepped abutments. 130
  4. In a device of the class described, the combination of a recording mechanism, a group of record holders, holder selector means including projecting pins of different lengths, selective index means including indexed abutments arranged in rows spaced apart the same distance as the distance between said pins to position the selector means to receive a desired record holder, transfer means for moving a selected record holder from said group to said selector means and for restoring the same to said group, and the selector means being adapted to position a selected record holder to receive an impression upon its record from said recording mechanism. 140
  5. In a device of the class described, the combination of a recording mechanism, a group of record holders, selector means including a finder having relative movable transfer means engageable with all of said holders of said group and adapted to engage a selected record holder to the exclusion of the others, said finder being adapted to remain in its position of selection for the return of said record holder to said group, and an advance movable with said finder to the point of selection and movable independently thereof to position said record holder to cooperate with said recording mechanism. 150
  6. In a device of the class described, the combination with a recording mechanism, a group of record holders, advance means for positioning selected holders in cooperative relation to said recording mechanism, selector means for moving said advance means to a point of selection, said selector means including a finder having relatively movable means engageable with all of said holders and adapted to engage the selected record holder to the exclusion of the others, transfer means for moving said relatively movable means to position the selected record holder in cooperation with said advance means, and said finder remaining stationary upon movement of said advance means whereby to cooperate in restoring the selected record holder to its original location in said group. 160
  7. In a device of the class described, a recording mechanism, a group of record holders, an advance for receiving and positioning selected holders in cooperative relation to said recording mechanism, a finder for moving said advance to a point of selection, said finder having an elongated slot, a transfer pin movably associated 170

- with said slot to move a selected record holder from said group into engagement with said advancer, said transfer pin having means engageable with all of said holders of said group and adapted to engage the selected record holder to the exclusion of the others, and a transfer plate cooperating with said transfer pin to remove a selected record holder from said group and to restore the same thereto. 80
10. 8. In a device of the class described, a recording mechanism, a group of record holders each having a notched edge, an advancer for receiving and positioning selected holders in cooperative relation to said recording mechanism, a finder having an elongated slot, said advancer movable with and independently of said finder and having an elongated slot in alignment with the slot of the finder and opening out into the edge of the advancer, a transfer pin associated with said slots of said finder and advancer, said transfer pin being disengageable from the slot of the advancer to permit independent movement of the latter, said transfer pin having a portion movable through the notches in said records and adapted to engage the notch of the selected record holder, and a transfer plate having connection with said transfer pin for moving the same to move the selected record holder into the advancer mechanism and to return the same to said group. 85
15. 9. In a device of the class described, a recording mechanism, a group of record holders each having a notched edge, an advancer for receiving and positioning selected holders in cooperative relation to said recording mechanism, a finder having an elongated slot, said advancer movable with and independently of said finder and having an elongated slot in alignment with the slot of the finder and opening out into the edge of the advancer, a transfer pin associated with said slots of said finder and advancer, said transfer pin being disengageable from the slot of the advancer to permit independent movement of the latter, said transfer pin having a portion movable through the notches in said records and adapted to engage the notch of the selected record holder, and a transfer plate having an elongated slot engageable with said transfer pin for moving the selected record holder into said advancer and returning the record to said group. 90
20. 10. In a machine of the class described, the combination of a master recording mechanism, an auxiliary recording mechanism located at either side thereof, a group of record holders disposed in alignment with said master recording mechanism, ways arranged at opposite sides of said group of record holders and extending to said auxiliary recording mechanisms, and means for selectively positioning any of said record holders in cooperative relation with said auxiliary mechanisms to receive impressions therefrom. 95
25. 11. In a machine of the class described, the combination of master and auxiliary typewriting machines, each having an individual set of type keys, a group of record holders, and means for selectively positioning any of said record holders in cooperative relation with an auxiliary typewriting machine to receive impressions therefrom, said master typewriting machine being operable to make an independent record of that produced by the auxiliary machine. 100
30. 12. The combination with a recording mechanism including a carriage, a group of record holders, each holder comprising a supporting part and a relatively movable record holding part, means for adjusting and retaining said record holding part in various positions with respect to said supporting part, means for selecting any one of said holders, means for positioning the holder in cooperative relation to the recording mechanism and including relatively movable parts, and means for coupling the movable parts of the positioning means and the record holder to said carriage to partake of its movements. 105
35. 13. The combination with a recording mechanism, a group of record holders, each holder comprising a supporting part and a relatively movable record holding part, an advancer mechanism including relatively movable parts for advancing a selected holder up to the recording mechanism, means for moving a selected holder into cooperative relation with said advancer mechanism, and means for coupling the relatively movable part of said advancer mechanism with said holder to cause their simultaneous movement. 110
40. 14. The combination with a recording mechanism including a carriage, a group of record holders, each holder comprising a supporting part and a relatively movable record holding part, means for adjusting and retaining said record holding part in various positions with respect to said supporting part, an advancer mechanism including relatively movable parts for advancing the selected holder to the recording mechanism, means for moving a selected holder into cooperative relation with said advancer mechanism, the supporting part of the record holder and the movable part of said advancer mechanism having cooperating means, and means for coupling said cooperating means with said carriage to cause the record holder and relatively movable part of the advancer to partake of the carriage movements. 115
45. 15. The combination with a recording mechanism, a group of record holders, each holder comprising a supporting part and a relatively movable record holding part, an advancer mechanism including an upright plate having a horizontal trough, and means for moving a selected record holder into the trough of said advancer mechanism. 120
50. 16. The combination with a recording mechanism including a carriage, a group of record holders, each holder comprising a supporting part and a relatively movable record holding part, an advancer mechanism including a part having a horizontal trough for the reception of the supporting part of a selected record holder, said advancer having a relatively movable part movable longitudinally thereof, means for moving a selected holder into said trough, and means for connecting the record holder in said trough with said carriage. 125
55. 17. The combination with a recording mechanism, a group of record holders, means for advancing a selected holder to the recording mechanism, said means being movably mounted along one side of said group of holders, and selector means movable longitudinally of the group of holders and operable to move a selected holder laterally into and out of said advancing means. 130
60. 18. The combination with a group of record holders having notches therein to define a passageway through the group, and a selector movable through said passageway for cooperation with any of said record holders and movable substantially transversely of said passageway to remove a selected record holder from said group. 135
65. 19. The combination with a group of record 140
70. 75. 145

- holders having notches therein to define a passageway, and a selector including a swinging part, a rectilinearly movable part movable longitudinally through said passageway, and a connection between said parts enabling said rectilinearly movable part to move independently of the swinging part for selecting a desired holder and to move concurrently with said swinging part but in a rectilinear path.
- 10 20. The combination of a group of record holders having notches therein to define a passageway, a selector mechanism comprising a plate disposed beneath the group and movable transversely thereof, said plate having ways therein, an actuator engaging one of said ways, a transfer member operating in another of said ways and having a portion operating in the passageway of the holders to engage a selected holder and remove it from the group upon operation of the actuator.
- 15 21. The combination with a group of record holders each having its lower edge notched said notches being aligned to define a passageway longitudinally through said group, a member disposed beneath said group and movable laterally thereof, and an upstanding transfer pin movable with said member and relative to the same for movement through the passageway defined by the notches of said record holders for engagement 25 with the selected holder and removal of same from said group.
- 20 22. The combination with a group of record
- holders, holder selector means movable longitudinally of said group and having abutment means, a plurality of movable abutments independent of said group of record holders and spaced different distances from the group and movable into and out of the path of the abutment of the selector means to place the same in position to engage the selected holder, and means for moving the selector means laterally of the group to remove the selected holder laterally from the group.
- 25 23. The combination with a group of record holders, holder selector means arranged for movement along one side of said group and having an abutment, a plurality of selector keys arranged different distances from said group for selective abutment with the abutment of the selector means to place the same in position to engage the selected holders, and means for moving the selector means laterally of the group to move the selected holder laterally from said group.
- 30 24. The combination with a group of record holders, an advancer for receiving a selected holder, a finder for moving said advancer to a point of selection, transfer means movably associated with said finder for engagement with a selected holder, means for moving the transfer means relative to said finder for withdrawing the selected holder from said group and positioning the same in said advancer, and means for moving said advancer independently of said finder.
